Atteys

UNITED STATES PATENT OFFICE.

DANIEL C. MULVIHILL, OF HANNIBAL, MISSOURI.

DEVICE FOR REMOVING SAND FROM METAL CASTINGS.

Application filed January 19, 1925. Serial No. 3,847.

This invention relates to devices for loosening and removing sand and sand cores from castings, and the principal object of the invention is the provision of new and improved 5 sand core loosening and sand removing device that may be inserted through holes in castings for loosening the sand or sand cores in recesses formed by the cores in the casting operation whereby the same may be poured 10 from the cast article.

Another object of the invention is the provision of new and improved means for removing sand from the interior of cast wheels, that is flexible, that may be readily inserted 15 in the recess containing the core, that is simple in construction, cheap to manufacture, easily manipulated, readily assembled, efficient in operation, and that is not likely to become broken or get out of order.

20 Other and further objects and advantages of the invention will appear from the following description taken in connection with the accompanying drawings, in which

Fig. 1 is a side elevation of a car wheel 25 showing the invention associated therewith; and

Fig. 2 is a vertical section on line 2—2 of Fig. 1.

In casting car wheels of the double plate 30 center type an annular recess is formed about the hub, and after the casting operation the sand core is removed. Heretofore this has been done at considerable time and expense. With the present invention the operation of 35 removing the sand core is accomplished with ease and dexterity.

On the drawing the reference character 10 designates a car wheel which has been cast with an annular recess 11 about the hub 12, 40 with a plurality of openings 9 leading therefrom, as is usual in such constructions, the recess being formed by the sand core 13. The wheel is shown as being supported on a track 14, and guided thereon by a guide 15. It is 45 understood that the track and guide are used for convenience in transporting the wheel from one position to another, and are not absolutely necessary to the operation of the sand loosening device, although they will 50 hold the wheel in an advantageous position

for permitting the loosened sand of the core to run out through the holes 9. Any suitable support may be employed, or none at all, as occasion, necessity or convenience may require.

55 In the form of the device selected to illustrate one embodiment of the invention, a shaft 16, which is preferably the conventional type of flexible shaft, is adapted to be rotated by suitable means, such as the motor 17. The 60 flexible shaft 16 is provided with a flexible protecting sheath or casing 18, as is usual in such constructions. The motor 17 may be of any suitable shape or type.

The outer end of the flexible shaft 16 is provided with a chuck 19 comprising the clamping jaws 20 and the chuck sleeve 21 for operating the jaws.

65 A flexible tool 22 is adapted to have one end secured to the shaft 16 by the clamping jaws 70 20 in the usual manner. The tool 22 may be of any suitable material. It has been found by experiment that a length of wire cable constitutes an excellent tool for this purpose. It is cheap and at the same time exceedingly 75 efficient.

If desired the sheath or casing 18 may be provided with a handle 23 adjacent to the head 19 for manipulating the tool. A switch 25 for controlling the motor may be mounted 80 on the handle 23.

In the operation of the device, the tool is inserted in holes 9 in the side of the wheel and the rotation of the tool will readily loosen the sand which will run out of the recess 85 through the openings. By inserting the tool in two or more of the openings the sand may be loosened and detached from all portions of the walls of the recess, with ease and celerity.

90 It is thought from the foregoing taken in connection with the accompanying drawings that the construction and operation of my device will be apparent to those skilled in the art, and that various changes in size, shape, proportion and details of construction may be made without departing from the spirit and scope of the appended claim.

I claim as my invention:

A device for loosening sand cores in hol- 100

low metal castings, comprising a flexible shaft, means for operating said shaft, a long flexible tool formed from a single length of twisted wires, a head on the end of said shaft
5 for securing the end of said tool thereto, whereby said tool may be inserted through a core hole in a casting with the head on the outside of said casting, for loosening said core and reducing the same to loose sand, and a handle member on said shaft adjacent to 10 said head.

In testimony whereof I affix my signature.

DANIEL C. MULVIHILL.
